UNITED STATES PATENT OFFICE.

WILLIAM SPALCKHAVER, OF NEW YORK, N. Y., ASSIGNOR TO ROBERT HOE, OF NEW YORK, N. Y.

DELIVERY MECHANISM FOR PRINTING-MACHINES.

SPECIFICATION forming part of Letters Patent No. 687,280, dated November 26, 1901.

Application filed March 18, 1901. Serial No. 51,597. (No model.)

To all whom it may concern:

Be it known that I, WILLIAM SPALCKHAVER, a citizen of the United States, residing at New York, county of Kings, and State of New York, have invented certain new and useful Improvements in Delivery Mechanisms for Printing-Machines, fully described and represented in the following specification and the accompanying drawings, forming a part of the same.

This invention relates to certain improvements in printing-machines. In certain kinds of fast newspaper-printing machines the product from the delivery mechanism—as, for instance, the cutting and collecting cylinders—passes into a throat or passage through which it passes as it is led out of the machine. It sometimes happens that the papers are not carried away fast enough by the tapes or other feeding-out mechanism employed, and a choke occurs in the throat.

It is the object of this invention to produce a mechanism by which choke in the delivery throat or passage may be prevented or instantaneously relieved if it occurs, independent and perfectly automatic means being employed to return said mechanism to its normal position after the choke is relieved.

With this and other objects in view the invention consists in certain constructions and in certain parts, improvements, and combinations, as will be hereinafter fully described and then specifically pointed out in the claims hereunto appended.

In the accompanying drawings, which form a part of this specification, and in which like characters of reference indicate the same parts, Figure 1 illustrates in front elevation so much of a delivery mechanism of a printing-machine as is necessary to an understanding of the invention. Fig. 2 is a view similar to Fig. 1, showing the parts in a different position. Fig. 3 is a view similar to Fig. 1, but showing the parts in a different adjustment. Fig. 4 is a side elevation, partly in section, of the construction shown in Fig. 1. Figs. 5 and 6 illustrate a modification.

In the drawings, which illustrate one embodiment of the invention, 1 indicates a frame which may be of any usual form or configuration, and 2 and 3 indicate the ordinary cut-

ting, folding, and collecting cylinders, to which the web is led from guide-rolls 4. Located beneath the cylinder 2 are the ordinary nipping-rolls 5, to which the product is delivered—as, for instance, by means of an ordinary tucking-blade (not shown) or in any other suitable manner.

In the construction shown in Figs. 1 to 4, inclusive, two throats or passages lead from the nipping-rolls, either of which may receive the product therefrom. In the preferred form of the construction a set of tapes 6 forms a side of one of the throats and a set of tapes 7 forms a side of the other throat. It is to be understood, however, that any other suitable construction may be substituted for the tapes, if desired. The tapes 6 pass over a roll 8 and onward to any suitable delivery-point, (not illustrated,) and the tapes 7 pass over a similar roll 9. The return run of the tapes in the interest of clearness is not shown. The opposite side of the throats, of which the tapes 6 and 7 form one side, include movable guides which may be varied widely in construction. In the preferred construction, however, these guides consist of sets of fingers, the set of fingers which coöperate with the tapes 6 being marked 10 and the set of fingers which coöperate with the tapes 7 being marked 11. The fingers 10 are mounted on a shaft 12, which is suitably supported in the frame of the machine, and the fingers 11 are mounted on a similar shaft 13.

Means are preferably provided by which when either the fingers 10 or the fingers 11 are in operative position the product coming from the nipping-rolls will be directed into the proper path. While these directing or switching means may be varied in construction, each of the fingers 10 will be formed to provide a projection 14, this being accomplished by giving the fingers the shape shown or in any other suitable manner, and the fingers 11 will similarly be provided with projections 15. The nipping-rolls 5 consist, as usual, of a series of narrow drums or wheels mounted on shafts, and when either guide is in position the projections of its fingers will lie between the pairs of drums, thus preventing the product from being carried around the nipping-rolls.

The guides 10 and 11 are thrown into and out of position by rocking shafts 12 and 13, on which they are mounted, and these shafts will preferably be connected so that the movement of a guide into position occurs simultaneously with the movement of the other guide out of position. The shafts 12 and 13 may be rocked in any suitable manner, and the connections between the shafts to effect the simultaneous movement of the guides may be of any suitable construction. As shown, the end of the shaft 12 is provided with a casting which is formed to provide a handle 16 and an arm 17. The shaft 13 is provided with another casting, which has projecting therefrom an arm 18. The arms 17 and 18 are connected by a link 19. When, therefore, the shaft 12 is rocked, the two guides will be operated, one being thrown into position and the other out of position. Means are provided, which may be of any suitable description, to move the guides into and out of position when choke occurs, which is apt to occur between the guide and the set of tapes with which it coöperates. In the preferred form of the construction these means consist of a rock-lever 20, pivoted to the frame of the machine at 21. This lever may be provided with means, as an extension 22, by which it may be operated, said extension passing through a platform 46, which is located in front of the delivery. The extension 22 is preferably arranged to be operated by the foot, and the lever 20 has connected to it a rod 23, which extends through a puppet 24, secured to the frame of the machine, and carries on its upper end an operating cross-bar 25. Between the cross-bar 25 and the puppet 24 is located a spring 26, which tends to normally hold the rod and lever up out of operative position. The castings, heretofore referred to as mounted on the shafts 12 and 13, are preferably provided with arms 28 and 29, and the arm which is secured to the shaft of the guide which is in operative position is so located as to be struck by the operating-bar 25 when the lever 20 is depressed. This will rock the shaft belonging to the guide and move the guide backward away from its coacting set of tapes, so as to allow the product to drop onto the floor.

Means which are independent of the opening means are provided for returning each guide to its operative position as soon as the operating-lever 20 has been released. In the preferred form of the construction these means consist of a spring or its well-known equivalent—a weight. While the springs may be variously applied in the preferred form of the construction, the castings, before referred to as mounted on the shafts 12 and 13, are provided with arms 30 and 31. The arm 30 has secured thereto a rod 32, which passes through a puppet 33, secured to the frame, and is provided with a collar 34. Between the collar 34 and the puppet 33 is located a

spring 35, which will be compressed by the movement of the arm 30, produced by rocking shaft 12. Similarly the arm 31 has connected to it a rod 36, which passes through a puppet 37, and is provided with a collar 38, a spring 39 being located between the puppet and the collar. These spring-rods and the arms to which they are connected are preferably so arranged that when the shaft 12 is operated by its handle to throw either guide in or out of operative position the arms and springs will pass the center, and the springs will therefore hold the guides in their adjusted position. The movement of the guides produced by the lever 20 and the cross-bar 25, which is connected thereto, is not sufficient to cause these springs to pass the center. It is apparent, therefore, that as soon as the rock-lever 20 is released the guides will immediately move back into operative position.

Sets of tapes 40 and 41, which may be mounted in any suitable or usual manner, co-operate with the tapes 6 and 7 to forward the product after it leaves the guides 10 and 11.

In the construction shown in Figs. 5 and 6 a single throat only is employed. This is formed, as before, by a set of tapes, (marked 6,) and coöperating with these tapes is a movable guide formed of fingers 10. The construction corresponds in all respects with that shown in Figs. 1 and 2, except that the rock-lever 20 instead of being pivoted at one of its ends is pivoted in the middle to a bearing 42, secured to the floor of the machine. The rod 20 is connected to an arm 43, mounted on the shaft 12, as before. The casting, which has been before described, is not used in this form of the construction, and instead of springs, which return the guide, an arm 44, carrying a weight 45, is employed.

While the specific means heretofore described for carrying the invention into effect constitutes a preferred embodiment of the invention, it is to be understood that the invention is not to be limited thereto.

What is claimed is—

1. The combination with a delivery mechanism, of a throat or passage which receives the product therefrom, one side of said throat including a movable guide, means for moving said guide away from the opposite side of the throat to prevent choke, and independent means for returning the guide to its normal position, substantially as described.

2. The combination with a delivery mechanism, of a throat or passage which receives the product therefrom, one side of said throat including a movable guide, means for moving said guide away from the opposite side of the throat to prevent choke, and independent means for automatically returning the guide to its normal position, substantially as described.

3. The combination with a delivery mechanism, of a throat or passage which receives the product therefrom, one side of said throat

- or passage including a movable guide, means for moving said guide away from the opposite side of the throat or passage to prevent choke, and a device, such as a spring or its equivalent for returning the guide, substantially as described.
4. The combination with a delivery mechanism, of a throat or passage for receiving the product therefrom, one side of said throat or passage including a pivoted guide, a lever, means whereby the lever moves the guide to open the throat, and independent means for returning the guide to its normal position when the lever is released, substantially as described.
5. The combination with a delivery mechanism, of a throat or passage for receiving the product therefrom, one side of said throat or passage including a pivoted guide, a lever, means whereby the lever moves the guide to open the throat, and independent means for automatically returning the guide to its normal position when the lever is released, substantially as described.
6. The combination with a delivery mechanism, of a throat or passage for receiving the product therefrom, one side of said throat or passage including a pivoted guide, a rock-lever, connections whereby a movement of the lever rocks the guide to open the throat, and means for automatically returning the guide to its normal position when the lever is released, substantially as described.
7. The combination with a delivery mechanism including a pair of nipping-rolls, of a throat or passage into which said nipping-rolls deliver, one side of the throat or passage being formed by tapes and the other side including a pivoted guide, a rock-lever, connections whereby a movement of the lever rocks the guide, and means for automatically returning the guide to its normal position when the lever is released, substantially as described.
8. The combination with a delivery mechanism, of a series of tapes forming one side of a throat or passage arranged to receive the product from said mechanism, a movable guide including a series of fingers co-operating with said tapes, a shaft on which said fingers are mounted, a rock-lever, connections whereby the movement of the lever rocks the shaft, and means for automatically returning the shaft when the lever is released, substantially as described.
9. The combination with a delivery mechanism, of two throats or passages either of which may receive the product from said mechanism, one side of each of said throats or passages including a movable guide, means for throwing either of said guides into operative position, means for moving the guide which is in operative position to prevent choke in the throat, and means for automatically returning the guide to its operative position when the moving means is released, substantially as described.
10. The combination with a delivery mechanism, of two throats or passages either of which may receive the product from said mechanism, one side of each of said throats or passages including a movable guide, means for simultaneously throwing one of the guides into position and the other out of position, means for moving the guide which is in operative position to prevent choke in the throat, and means for automatically returning the guide to its operative position when the moving means is released, substantially as described.
11. The combination with a delivery mechanism, of two throats or passages, either of which may receive the product from said mechanism, one side of each of said throats including a movable guide, a projection on each guide operating as a switch, means for throwing either guide into operative position, means for moving the guide which is in operative position to prevent choke, and means for automatically returning the guide when the moving means is released, substantially as described.
12. The combination with a delivery mechanism, of two throats or passages, either of which may receive the product from said mechanism, one side of each of said throats including a movable guide, a projection on each guide operating as a switch, means for simultaneously throwing either guide into operative position and the other out of operative position, means for moving the guide which is in operative position to prevent choke, and means for automatically returning the guide when the moving means is released, substantially as described.
13. The combination with a delivery mechanism, of two throats or passages, either of which may receive the product from said mechanism, one side of each of said throats including a movable guide, means for throwing either guide into operative position, a lever, and means whereby said lever may operate either guide to relieve choke, and means for automatically returning the guide after the lever is released, substantially as described.
14. The combination with a delivery mechanism, of two throats or passages, either of which may receive the product from said mechanism, one side of each of said throats including a movable guide, means for simultaneously throwing either guide into operative position and the other out of operative position, a lever, means whereby said lever may operate either guide to relieve choke, and means for automatically returning the guide after the lever is released, substantially as described.
15. The combination with a delivery mechanism including a pair of nipping-rolls, of two throats or passages, either of which may receive the product from the rolls, one side of each of said throats or passages including a movable guide consisting of a set of fingers,

shafts, one for each set of fingers, connections between the shafts, means for operating one of the shafts to throw either guide into or out of operative position, a lever, means whereby the lever moves either guide to prevent choke in the throat, and means for automatically returning said guide to its operative position when the lever is released, substantially as described.

- 10 16. The combination with a delivery mechanism including a pair of nipping-rolls, of two sets of tapes, movable guides, one for each set of tapes, each of said guides consisting of a set of fingers, projections on the fingers forming a switch, a shaft on which the fingers are mounted, connections between

the shafts, an operating-lever connected to one of the shafts, a rock-lever, an operating-rod connected to the lever, an operating-bar carried by the rod, an arm carried by each shaft with which said bar coöperates and springs connected to each shaft for returning the shaft when the lever is released, substantially as described.

In testimony whereof I have hereunto set 25 my hand in the presence of two subscribing witnesses.

WILLIAM SPALCKHAVER.
